(57) **CLAIM**

I claim the ornamental design for a car spoiler device, as shown and described.

DESCRIPTION

FIG. 1 is a perspective view of the car spoiler device.

FIG. 2 is a top view of the car spoiler device.

FIG. 3 is a bottom view of the car spoiler device.

FIG. 4 is a front view of the car spoiler device.

FIG. 5 is a rear view of the car spoiler device.

FIG. 6 is a side view of the car spoiler device.

FIG. 7 is a side view of the car spoiler device; and,

FIG. 8 is a perspective view of the car spoiler device on a car.

In the drawings, the broken lines depict portions of the car spoiler that form no part of the claimed design. The vehicle in FIG. 8 shown in broken lines is for environmental subject matter only and forms no part of the claimed design.
